UNITED STATES PATENT OFFICE.

WILLARD E. DOW, OF BRAINTREE, MASSACHUSETTS.

MAGNETO-FRAME.

1,195,921.

Specification of Letters Patent. Patented Aug. 22, 1916.

Application filed August 21, 1913. Serial No. 785,959.

To all whom it may concern:

Be it known that I, WILLARD E. Dow, a citizen of the United States, and resident of Braintree, county of Norfolk, Commonwealth of Massachusetts, have invented an Improvement in Magneto-Frames, of which the following description, in connection with the accompanying drawings, is a specification, like characters on the drawings representing like parts.

The present invention relates to bodies or frames for magnetos such as used for ignition systems of internal combustion engines and the like.

The invention consists in an improved construction of body of this kind wherein an integral unit which may be produced by a single casting is fashioned and arranged to hold in rigid and secure assemblage all the operative parts of the magneto, including the field magnets, the armature, the distributor, the interrupter, etc., which for their proper respective collocation in the machine only require to be fixed to this one-piece body by any usual securing means. In accordance with my invention not only are all these operative parts held securely and accurately assembled by this one-piece body, the parts of which interbrace one another, but this one-piece, integral unit construction of the body, including inclosing housing portions for the projecting operative parts makes a much more completely moisture proof device than has hitherto been produced. Further, since the entire supporting and housing frame is cast at a single operation, the expense of production is very materially lessened not only as to the casting, but also in the eliminating of the assembly of the parts which have hitherto made up the magneto frame. I also preferably fit in, the pole shoes pieces of the field magnets at the sides of my improved frame, in a manner so that the relatively soft metal which comprises the frame casting is adapted to shrink around and tightly hold the shoe pieces without any separate fastening means therefor.

The above and other objects and features of the invention will be better understood from the following detailed description taken in connection with the accompanying drawings and will be thereafter pointed out in the appended claims.

Referring to the drawings: Figure 1 is a perspective view of a magneto frame constructed in accordance with my invention;

Fig. 2 is an end view thereof; Fig. 3 is a side elevation; and Fig. 4 is a transverse section on line 4-4 of Fig. 3.

My improved frame is preferably cast of bronze or like non-magnetic metal and the illustrative form selected for the present showing consists in a generally rectangular oblong block 10 having its sides somewhat tapering as at 11, the major portion of these sides being recessed as at 12 to form seats for the ends of the U-shaped permanent field magnets *m* which constitute the magnetic field. This block is longitudinally bored as 13 to receive the armature which is journaled in suitable ball bearings fitted in the ends of the frame, one of these ends having a reduced projecting sleeve 14 especially for this purpose, and the other or distributor 75 end of the frame having the full size of the armature bore carried to its extremity as at 15, the armature bearings at this end along with the interrupter mechanism being suitably mounted in this end of the bore. The 80 pole shoes, usually of cast iron as indicated at 16, are positioned at the sides of the block, being held in the casting by the shrinkage of the surrounding metal and their outer sides constitute the major portions of the 85 bottoms of the magnet seats 12 so that the magnet extremities are contiguous thereto while their inner sides open into the bore of the frame and are shaped to conform thereto as seen at 17. As a means for mounting 90 the distributor mechanism I form at the interrupter end of the frame an upwardly projecting face portion 18 with a bearing sleeve 18' projecting from the back thereof and also having an integral connection with the 95 top of the frame block proper, this face portion and bearing sleeve being provided with a bearing bore 19 for the distributor gear, the face portion having a forwardly projecting shroud flange 20 which constitutes 100 part of a housing for the distributor mechanism, this shroud housing being extended down and containing the end of the bore 15 as indicated at 21. It is to be observed that this shroud flange or housing thus integrally 105 formed with the base portion of the frame block, and projecting up integrally with the face portion 18 which also rises integrally from the frame block, makes a particularly rigid and reliably interbraced mounting and 110 support, adapted to hold the working parts accurately and in precise alinement without possibility of even the slightest dislocation.— as well as protecting the vital parts of the

mechanism, viz: the distributor and interrupter from moisture or wet of any kind. It is to be further noted that my improved construction including the magneto body 5 with the integral sleeve 18' formed on the top thereof in conjunction with the integral shroud flange 20 provides a one piece construction wherein the several portions mutually strengthen and interbrace one another 10 so that a maximum of rigidity with a minimum of material is possible, along with the before mentioned advantage of insuring freedom from ingress of moisture. It will be understood that in this combination of 15 elements, the formation of the shroud flange 20 at the face of the body is of value and importance since it thus combines the functions of a protecting housing for the distributor and interrupting gearing and as a 20 stiffening and strengthening flange for the distributor bearing. At the other end of the stand is formed a cylindrical extension 22 for the slide ring, the before mentioned reduced bearing sleeve 14 projecting integrally from this extension. A short threaded 25 collar 23 projects up from the top of extension 22 having a bore adapted to receive the carbon brush holder which may be formed with threads to engage the threads of this 30 collar. Thus this end of the device is also protected to the highest possible degree against the entrance of moisture and the integral formation contributes to the strength and rigidity of the entire unit as well as 35 greatly reducing the cost that would be involved in producing the several parts separately and machining them so that they would fit together accurately as required.

It is to be observed that the sleeve 14 has 40 its outer face extended in to fit closely around the armature shaft as indicated at 24 so as to better serve as a housing protector.

The operative parts that are supported 45 and held assembled by my improved frame are indicated in outline in dotted lines so as to make the structure of the frame itself appear more clearly and as these operative parts form no part of the present invention. 50 The field magnets are indicated at *m*, the armature shaft at *s*, an outline of the interrupter at *i*, this being housed in the bore extension 15, and a block or plate being indicated at *d* which carries and affords an 55 outer bearing for the distributor and is suitably fixed to the outer edge or face of the flange 20. It will be understood that the specific form and character of these parts is not material to the present invention, the 60 only essential being an adaptability for assemblage to be held in coöperative relation on the frame set forth.

My improved frame thus formed as an

integral unit can be made of the requisite strength and rigidity while considerably 65 lighter than a built-up frame, since the several parts of the integral formation are so arranged and disposed as to mutually brace and stiffen one another and thus expense is largely reduced in labor as well as cost of 70 material, with the further accruing advantage of an integral frame that is also so far as possible a completely tight housing for the working parts to protect the same from moisture.

I do not desire to be limited to the precise embodiment of the invention herein shown and refer to the appended claims rather than to the foregoing description to indicate the scope thereof.

Having described my invention, what I claim as new and desire to secure by Letters Patent is:

1. A magneto frame, formed as an integral unit with a longitudinal armature receiving bore and lateral recessed seats for the field magnets, there being pole shoes held by the surrounding metal to fill the space between the bottoms of said seats and said bore, and said frame being equipped with extensions at its ends integral therewith, one of said extensions having an upwardly projecting sleeve to hold the bearing for a distributor mechanism, there being an upwardly extending shroud integral with 95 the body of said frame and also with said sleeve to serve as a housing for the interrupter and distributor gearing, whereby it and the sleeve are mutually interbraced, and the extension at the other end being 100 equipped to serve as a mounting and housing for the armature shaft, the slide ring and the carbon brush.

2. A magneto frame formed as an integral unit with a bore for the armature and provision for fixing a field magnet in proximity thereto, said frame having an integral upward and forward extension affording a bearing and housing for the distributor and interrupter mechanism, and 110 having also formed in one piece therewith a rearward extension equipped to serve as a mounting and housing for the armature shaft, the slide rings and the carbon brush, said rearward extension constituting a complete closure for the rear end of the armature bore with a passage through which the armature shaft is fitted.

In testimony whereof, I have signed my name to this specification, in the presence of 120 two subscribing witnesses.

WILLARD E. DOW.
